REDUCTION OF INTERFERENCE IN
THERMIONIC VALVE CIRCUITS

Peter William Willans, Hampstead, London, England, assignor to Electric and Musical Industries Limited, Middlesex, England, a company of Great Britain

Application May 26, 1933, Serial No. 672,997
In Great Britain May 26, 1932

15 Claims. (Cl. 250—20)

The present invention relates to the reduction of interference in thermionic valve circuits.

It is known for various purposes to provide a tuned circuit common to the anode-cathode and grid-cathode circuits of a thermionic valve. For example such a tuned circuit has been made resonant at or near the lower limit of a band of frequencies to be amplified for the purpose of rendering the amplification more nearly uniform over the band. In another known arrangement the potential differences developed across such a tuned circuit in a wireless receiver have been at the "wanted" frequency (that is to say the frequency of the carrier to be received) and have been passed on to the detector.

It has also been proposed to connect an impedance, such as a choke, in parallel with a condenser between the cathode of a thermionic amplifier valve and the negative terminal of the source of anode current supply, for the purpose of providing a desired frequency response characteristic. The condenser has been given a value such that its impedance for the lowest frequency at which the amplifier works is small in comparison with the impedance which it shunts. The resonant frequency of the impedance and condenser in parallel has therefore been below the operating range of the amplifier.

The present invention is concerned with the method of reducing the amplitude of an unwanted interfering oscillation according to which the effective amplification of a thermionic valve is reduced at the frequency or frequencies of the unwanted oscillations with the aid of means producing an anti-regenerative feed-back from the anode circuit to the grid circuit of the valve. The said means may take the form of a reactive impedance or a combination of reactive impedances common to the anode-cathode and grid-cathode circuits of the valve. The amplification will in this arrangement be least when the impedance of the circuit common to the anode and grid circuits is a maximum.

According to the present invention, a thermionic valve circuit comprises a resonant circuit tunable to a wanted frequency, and a thermionic valve having means comprising a second resonant circuit common to its anode and control grid circuits and adapted to produce anti-regenerative feedback at an unwanted frequency from the anode circuit to the control grid circuit of said valve, the tuning controls of both said resonant circuits being mechanically coupled for simultaneous actuation.

In a superheterodyne receiver, where, for ex-

ample, the intermediate frequency circuits are fixedly tuned, it may be unnecessary to make the second resonant circuit tunable.

The invention accordingly provides a superheterodyne receiver in which there is employed a thermionic valve having in common with its anode-cathode and grid-cathode circuits a resonant circuit comprising an impedance element or combination of impedance elements, the impedance of which is much higher at one or more unwanted frequencies than at a wanted frequency.

In the case of a superheterodyne wireless receiver, if it is desired to receive a modulated carrier of frequency 1000 kilocycles and if the intermediate frequency amplifier is tuned to 100 kilocycles, the local oscillator may be tuned to 900 kilocycles. If there should be an unwanted oscillation at a frequency close to 800 kilocycles, or if there should be a harmonic of a strong unwanted station at a frequency of 800 kilocycles, it will cause second channel interference by beating with the local oscillations to produce the intermediate frequency. According to a feature of the invention, therefore, in a superheterodyne receiver as set out in the preceding paragraph, said resonant circuit is tuned or made tunable to a frequency or band of frequencies at or within which second channel interference may occur.

A further application of the invention is to the purification of the oscillations generated by a beat oscillator. In generating oscillations of relatively low frequency, for example audio frequency, by beating together two oscillations of relatively high frequency and rectifying the resulting beats, it is known that if one of the two relatively high frequency oscillations is free from harmonics, the resulting beat frequency oscillations will also be free from harmonics. Harmonics may for example be introduced by a linearity of the detector. It is usual to keep the frequency of one of the high frequency oscillations constant and to vary the frequency of the other high frequency oscillations when it is desired to vary the frequency of the beats.

According to this invention, a beat oscillator comprises two sources of oscillations of different frequencies, and a detector valve having means comprising a resonant circuit common to its anode-cathode and grid-cathode circuits for producing anti-regenerative feed-back from the anode circuit to the grid circuit of said detector valve at one or more of the harmonic frequencies of one of said sources of oscillations.

Further, the present invention may be applied to wireless receivers adapted to operate over two

or more different frequency ranges; in such receivers, it may be found that oscillations within the higher frequency range tend to "break through" and cause interference when the receiver is operated over the lower frequency range.

According to a feature of the present invention, a wireless receiver of this type comprises a tunable input circuit and switching means for changing the frequency range over which said circuit is tunable, and a thermionic valve having means comprising a resonant circuit common to its anode-cathode and grid-cathode circuits for producing anti-regenerative feed-back from the anode circuit to the grid circuit of said valve, over the whole or a part of one of the frequency ranges to which said input circuit is tunable.

The resonant circuit may be thrown into and out of circuit automatically when the range-changing switching means are operative. It may, if desired, take the form of a simple inductance.

The invention will be described by way of example with reference to the accompanying drawings, in which

Fig. 1 is a circuit diagram of a superheterodyne receiver,

Fig. 2 is a further circuit diagram of a superheterodyne receiver,

Fig. 3 is a circuit diagram of a receiver for operation over two frequency ranges,

Figs. 4 and 5 show two alternative resonant circuits for use in association with the receiver of Fig. 3, and

Fig. 6 shows an audio-frequency beat oscillator.

Referring to Fig. 1, an input transformer comprises a primary winding 1, connected in a suitable antenna-earth circuit, and inductively coupled to a secondary winding 2 which is shunted by a variable condenser 3, and is connected between the control grid of a screened grid first detector valve 4, and earth. The screen grid 5 of the valve 4 is connected through a coil 6 to a point in a source 7 of high tension current, and the coil 6 is coupled by means of a coil 8 to a source 9 of local oscillations. The frequency of the oscillations generated by the source 9 is determined by a variable condenser 10. The anode 11 of the valve 4 is connected to the source 7 of high tension current through a parallel resonant circuit 12 tuned to the desired intermediate frequency.

The cathode 13 of the valve 4 is connected to earth through a biasing resistance 14 shunted by a by-pass condenser 15, and a parallel resonant circuit comprising an inductance coil 16 in parallel with a variable condenser 17. The broken lines indicate that the variable condensers 3, 17 and 10 are ganged for simultaneous actuation by a single control.

When the input circuits 2, 3 is tuned to a wanted frequency f_1 , and the local oscillator 9 is generating oscillations of frequency $f_1 \pm f_2$, the circuit 16, 17 may be tuned to a frequency $f_1 \pm 2f_2$, that is, the frequency of the second channel or image frequency interference corresponding to the frequency f_1 . If the tuning of the circuit 16, 17 is sharp, there will be substantially no negative or anti-regenerative feed-back at the frequency f_1 , while the amplification of the valve 4 at the frequency $f_1 \pm 2f_2$ will be considerably reduced due to negative feed-back at this frequency.

If an impedance is arranged in the anode circuit of a valve of magnification factor m , it can be shown that the effect of making this imped-

ance common to the grid circuit is to increase its effective value in the anode circuit in the ratio $1:1+m$. The circuit 16, 17 in the circuit described above is therefore $(m+1)$ times more efficient as a rejector of its resonant frequency than if it were connected in series in the input circuit, or in any other equivalent position.

The intermediate frequency circuit 12 is mutually coupled to a similar parallel resonant circuit 18 which is in the input circuit of an intermediate frequency amplifier 19. The latter feeds a second detector valve 20 which is coupled to a low-frequency amplifier 21 having a pair of output terminals 22. Between the cathode 23 of the second detector valve 20 and the negative terminal of a source 24 which supplies the anode current for the valve is connected a circuit comprising an inductance coil 25 in series with a parallel resonant circuit comprising an inductance coil 26 shunted by a fixed condenser 27. The circuit 26, 27 is fixedly tuned to the second harmonic of the intermediate frequency, and serves to produce anti-regenerative feed-back from the anode circuit to the grid circuit of the valve 20 at this frequency. The inductance coil 25 is arranged to have an impedance to the third and higher harmonics of the intermediate frequency which is considerably higher than its impedance at the intermediate frequency itself; anti-regenerative feed-back due to the inductance coil 25 therefore serves to reduce interference due to the third and higher harmonics of the intermediate frequency.

It may be observed here that in the interests of efficiency the impedance of the resonant feed-back circuit at the undesired frequency or frequencies should be as high as possible compared with the impedance of the valve with which it is associated. Subject to this consideration, the invention is not primarily concerned with the nature of the resonant feed-back circuit, and as has been mentioned, a simple inductance coil may in some cases constitute a suitable circuit. Broadly, any resonant circuit is suitable for use as a feed-back circuit which offers an impedance to one or more unwanted frequencies which is high compared with the impedance offered to a wanted frequency. Where the unwanted frequency is particularly close to the wanted frequency, it may be desirable to employ a complex feedback circuit which acts as a rejector at the unwanted frequency, and at the same time acts as an acceptor to the wanted frequency.

The superheterodyne receiver described with reference to Fig. 1 is of the type in which the antenna is coupled to the first detector without the interposition of a signal frequency amplifier stage, second channel interference being particularly manifest in such a receiver. Fig. 2 is a circuit diagram of a receiver having one stage of signal frequency amplification, and like parts in this figure are given the same references as in Fig. 1, with a dash suffix.

The primary winding 1' of the input transformer is coupled to an input circuit 2', 3' which is connected between the control grid of a screened grid signal frequency amplifier valve 28, and earth. Between the anode 29 of this valve and the source 7' of high tension current is connected the primary winding 30 of a high frequency transformer, the secondary winding 31 of which is connected in parallel with a variable condenser 32 between the control grid of a first detector valve 4' and earth.

Between the cathode 33 of the valve 28 and 75

earth is connected a biasing resistance 34 shunted by a bypass condenser 35, and, in series, a parallel resonant circuit comprising an inductance coil 36 in parallel with a variable condenser 37. 5 The broken line indicates that the variable condensers 3', 37, 32, 17' and 10' are ganged for simultaneous actuation. The intermediate frequency circuit 18' is in the input circuit of an intermediate frequency amplifier which is coupled 10 to a second detector feeding, in turn, a low frequency amplifier. The intermediate frequency amplifier, second detector and low-frequency amplifier are indicated at 38; the low-frequency output of the receiver is derived from a pair of 15 terminals 39.

The parallel resonant circuit 36, 37 is made resonant at the frequency of second channel interference corresponding to the signal frequency to which the input circuit 2', 3' is tuned, 20 and produces anti-regenerative feed-back at this frequency from the anode circuit to the grid circuit of the high-frequency amplifier valve 28. The circuit 16', 17' may be made resonant at the same frequency, or may be arranged to reduce 25 interference due to other causes. For example, this circuit may be tuned to the second harmonic of the frequency generated by the source 9' of local oscillations, or it may be fixedly tuned to the second harmonic of the intermediate frequency. In either case it may be replaced by a 30 low-pass filter circuit tuned or tunable to reject all harmonics of the intermediate frequency, or the frequency of the local source.

It is to be understood that many modifications 35 in the circuits of the receivers above described may be made within the scope of this invention. For example, it is not essential to couple the local source of oscillations to the screen grid circuit of the first detector valve; if desired, the local source may be coupled to an inductance coil 40 forming a part of the feed-back circuit.

Referring now to Fig. 3, which is a circuit diagram of a receiver adapted for operation over two frequency ranges, an input transformer comprises a primary winding in two sections 40 and 41. The primary winding is coupled to a secondary winding 42 and 43 which is shunted by a variable condenser 44 and connected between the control grid of a screened grid high frequency amplifier valve 45 and earth. The anode 46 of the valve 45 is connected to a source 47 of high tension current through the primary winding 48, 49 of a high frequency transformer, the secondary winding 50, 51 of which is shunted by a variable condenser 52 and is connected between the control grid 53 of a detector valve 54 and earth through a grid condenser 55. The control grid 53 is connected to earth through a grid leak 56. The screening grid 57 of the valve 45 is connected to a point in the source 47, and the detector valve 54 is coupled to a low frequency amplifier 58 having a pair of output terminals 59.

The sections 41, 43, 49 and 51 of the input and interstage transformers are provided with short-circuiting switches S₁, S₂, S₃ and S₄, these switches being closed when operating on the higher frequency band and open when operating on the lower frequency band. All four switches may be operated by a single control. It is found that 70 by reason, among other things, of stray capacities such as those between the switch contacts, the receiver may be responsive to a higher frequency signal when connected for operation over the lower frequency range, that is, when the 75 switches are open. The higher frequency signal

may tend to "break through" and cause interference with a programme within the lower frequency range.

The cathode 60 of the valve 45 is connected to earth through a biasing resistance 61 shunted by a by-pass condenser 62, and, in series, a resonant circuit comprising an inductance coil 63 in parallel with a condenser 64 which may be made variable. The circuit 63, 64 is made resonant to a frequency at which "break through" 10 is experienced, and by producing negative feedback at this frequency, tends to reduce the amplification of the valve 45 at this undesired frequency. A switch S₃ is provided to short-circuit the circuit 63, 64 when the switches S₁, S₂, S₄ 15 and S₅ are closed and the receiver is operating on the higher frequency range. The switch S₃ may be ganged with the switches S₁, S₂, S₃ and S₄ for simultaneous operation.

Reference will now be made to Figs. 4 and 5 20 which show two modifications of the receiver shown in Fig. 3. Certain of the elements of Fig. 3 are omitted from these figures, and elements which re-occur are given dash suffixes in Fig. 4 and double-dash suffixes in Fig. 5. In Fig. 4, a 25 second resonant circuit comprising an inductance coil 65 in parallel with a fixed condenser 66 is connected in series with the resonant circuit 63', 64' between the cathode 60' of the valve 45' and earth. The circuits 63', 64' and 65, 66 30 are made resonant at two frequencies at which "break through" occurs; more than two resonant circuits tuned to further "break through" frequencies may be employed if desired.

In Fig. 5, the cathode 60'' of the valve 45'' is 35 connected to earth through a low-pass filter comprising an inductance coil 63'' shunted by a condenser 67 in series with an inductance coil 68, the latter being shunted by a terminating resistance 69. The filter is designed to pass the 40 frequencies of the lower frequency range while presenting a high and substantially constant impedance to the frequencies of the higher range. The filter described above is given purely by way of example, and many other forms of impedance 45 networks may be employed within the scope of the invention.

Referring now to Fig. 6, which shows a beat type 50 audio-frequency generator, the triode valve 70 is arranged to produce oscillations of a fixed frequency, while the triode valve 71 is arranged to produce oscillations at a frequency which can be varied by adjustment of the condenser 72. The oscillations produced by the valve 70 are applied to the control grid 73 of a screen grid buffer valve 74, the anode 75 of which is connected to a high tension source 76 through a coupling coil 77. The coil 77 and the oscillator valve 71 are coupled to a coil 78 which is connected to the control grid 79 of a square law rectifying valve 80, and, 60 through a biasing battery 81, to earth.

The anode 82 of the oscillator valve 71 is connected to a high tension source 83 through a parallel resonant circuit comprising an inductance coil 84 in parallel with a fixed condenser 85. Connected to the cathode 86 of the valve 70, and to the control grid 87 through a grid condenser 88, is a coil 89 coupled to the coil 84. A grid leak 90 is connected between the grid 87 and the cathode 86, and a tapping point on the 70 coil 89 is connected to the grid 73 of the buffer valve 74.

The oscillator valve 71 is associated with similar circuits. Its anode 91 is connected through a resonant circuit comprising a coil 92 and the 75

condenser 72 to the source 76. The coil 92 is coupled to a grid coil 93, and a grid condenser 94 and a grid leak 95 are provided.

The anode 96 of the rectifier 80 is connected to a high tension source 97 through a high frequency filter comprising a choke 98 and two condensers 99, and the primary winding of a low frequency transformer 100, the secondary winding of which is associated with a pair of output terminals 101. The negative terminals of the high tension sources 97, 76 and 83 are earthed.

In a beat oscillator of this type it is found that a pure beat oscillation is obtained when the wave form of one of the two beating oscillations is pure, that is to say, undistorted by the presence of harmonics. The cathode 102 of the valve 80 is accordingly connected to earth through two circuits 103 and 104 each designed to reject a harmonic of the oscillation generated by the valve 70. The circuit 103 comprises a coil 105 in series with a fixed condenser 106, the series circuit being shunted by a fixed condenser 107. The series circuit 105, 106 is made resonant at the fundamental frequency, and the whole circuit is made to present a low impedance to the fundamental frequency of the oscillator 70, and a high impedance to the second harmonic. The circuit 104 similarly comprises a coil 108, and condensers 109 and 110, and is arranged to present a low impedance to the fundamental while presenting a high impedance to the third or another harmonic. If desired, the circuits 103, 104 may be replaced by a single impedance network designed to pass the fundamental and reject a number of harmonics.

I claim:

1. Apparatus comprising a thermionic valve having an input circuit and an output circuit, a resonant circuit connected to said input circuit and being tunable over a range of desired frequencies and a second resonant circuit, comprising an inductance coil in parallel with a condenser, common to said input and output circuits and being tunable simultaneously with the first resonant circuit, said second resonant circuit being tuned to an undesired frequency within said range and arranged to produce feed-back in anti-regenerative sense at said undesired frequency from said output circuit to said input circuit whereby currents of said undesired frequency are prevented in said output circuit.

2. Apparatus comprising a thermionic valve having an input circuit and an output circuit, an inductance coil associated electrically with one of said circuits, a variable condenser forming with said inductance coil a circuit tuned to a desired frequency and having an adjustable control element, a second inductance coil arranged to be common to said input and output circuits, a second variable condenser connected in parallel with said second inductance and having an adjustable control element, said second inductance coil and condenser constituting a circuit resonant to an undesired frequency, and means mechanically coupling said control elements whereby said condensers can be simultaneously adjusted and currents of said undesired frequency substantially eliminated from said output circuit.

3. A superheterodyne radio receiver comprising a thermionic valve having an input circuit and an output circuit, an inductance coil associated electrically with one of said circuits, a variable condenser forming with said inductance coil a circuit tuned to a desired signal frequency and having an adjustable control element, a second induct-

ance coil arranged to be common to said input and output circuits and a second variable condenser connected in parallel with said second inductance and having an adjustable control element, said second inductance coil and condenser constituting a circuit tuned to the image frequency of the desired signal frequency.

4. A superheterodyne radio receiver comprising a source of local oscillations, a thermionic valve coupled to said source and having an input circuit and an output circuit and a resonant circuit common to said input and output circuits, said resonant circuit being tuned to a harmonic of the oscillations generated by said source and being arranged to produce feed-back in anti-regenerative sense from said output circuit to said input circuit at said harmonic frequency.

5. A superheterodyne receiver of modulated carrier waves comprising a source of local oscillations adapted to beat with said carrier waves to produce oscillations of a beat frequency, a thermionic valve having an input circuit and an output circuit, means coupling said oscillation source to said input circuit and a resonant circuit common to said input and output circuits, said resonant circuit being tuned to a harmonic of said beat frequency.

6. A superheterodyne radio receiver comprising a source of local oscillations, a thermionic valve coupled to said source and having an input circuit and an output circuit and a rejector circuit comprising a plurality of impedance elements common to said input and output circuits, said rejector circuit having, at a plurality of frequencies which are harmonics of the frequency of the oscillations generated by said source, impedance values which are high compared with the impedance thereof at a desired frequency.

7. A superheterodyne radio receiver comprising a thermionic valve having an input circuit and an output circuit, and a rejector circuit comprising an inductance coil, a second inductance coil in series with said coil and a condenser arranged in parallel with said second inductance coil, common to said input and output circuits, said rejector circuit having much higher impedance values for harmonics of the intermediate frequency than for currents of the intermediate frequency.

8. A superheterodyne receiver for receiving modulated carrier oscillations comprising an input circuit, a source of local oscillations, means for applying said local oscillations to said input circuit, control means for varying the frequency of said local oscillations, an output circuit electrically associated with said input circuit, a rejector circuit common to said input and output circuits and arranged to reduce second channel interference in said output circuit, means for tuning said rejector circuit and means serving to couple said control and tuning means mechanically together for simultaneous operation.

9. A beat oscillator comprising two sources of oscillations of different fundamental frequencies, a detector valve having an input circuit and an output circuit, means for applying the oscillations from said sources to said detector valve, and a resonant circuit tuned to a harmonic of one of said fundamental frequencies and common to said input and output circuits adapted to produce feed-back in anti-regenerative sense from said output circuit to said input circuit at a frequency corresponding to a harmonic of the frequency of the oscillations generated by one of said sources.

10. A beat oscillator comprising two sources of oscillations of different fundamental frequencies,

a detector valve having an input circuit and an output circuit, means for applying the oscillations from said sources to said detector valve, and a resonant circuit tuned to a harmonic of one of 5 said fundamental frequencies and comprising a combination of impedance elements common to said input and output circuits arranged to produce feed-back in anti-regenerative sense from said output circuit to said input circuit at a plurality 10 of frequencies corresponding to harmonics of the frequency of the oscillations generated by one of said sources.

11. A beat oscillator comprising two sources of oscillations of different fundamental frequencies, 15 a detector valve having an input circuit and an output circuit, means for applying the oscillations from said sources to said detector valve, and a resonant circuit comprising a combination of impedance elements constituting an acceptor circuit 20 for the fundamental frequency of the oscillations generated by one of said sources, and a rejector circuit for a harmonic of that frequency, common to said input and output circuits arranged to produce feed-back in anti-regenerative sense from 25 said output circuit to said input circuit at said harmonic frequency.

12. A radio receiver comprising a thermionic valve having an input circuit and an output circuit, arranged for operation over a plurality of 30 frequency ranges, switching means arranged to change the range over which said circuits are operable, a resonant circuit common to the input and output circuits of said valve arranged to produce feed-back in anti-regenerative sense from 35 said output circuit to said input circuit at a frequency within one frequency range when said input and output circuits are connected for operation over another of said frequency ranges.

13. A radio receiver comprising a thermionic 40 valve having an input circuit and an output circuit, arranged for operation over a plurality of frequency ranges, switching means arranged to change the range over which said circuits are operable, a resonant circuit comprising a combination of impedance elements constituting a low- 45

pass filter arranged to offer an impedance to frequencies within a higher frequency range which is high compared with the impedance offered to frequencies within a lower frequency range common to the input and output circuits of said valve 5 and arranged to produce feed-back in anti-regenerative sense from said output circuit to said input circuit over a band of frequencies within said higher frequency range when said input and output circuits are connected for operation over 10 said lower frequency range.

14. A radio receiver comprising a thermionic valve having an input circuit and an output circuit, adapted for operation over a plurality of frequency ranges, switching means arranged to 15 change the range over which said circuits are operable, a resonant circuit common to the input and output circuits of said valve arranged to produce feed-back in anti-regenerative sense from said output circuit to said input circuit at a frequency within one frequency range when said input and output circuits are connected for operation over another frequency range, and switching means mechanically coupled to said range changing 20 switching means for short-circuiting said resonant circuit when said range changing switching means are operated to secure operation of said receiver over the higher of said frequency ranges.

15. A radio receiver comprising a thermionic valve having an input circuit and an output circuit 30 arranged for operation over a plurality of frequency ranges, a plurality of switches connected to said circuits to change the range over which said circuits are operable, a resonant circuit consisting of a coil connected in parallel with a capacitor common to the said input and output circuits and arranged to produce feed-back in anti-regenerative sense from said output to said input circuit at a frequency within one frequency range 35 when said input and output circuits are connected for operation over another of said frequency ranges and a single control means connected to operate said switches.

PETER WILLIAM WILLANS. 45
